VENTILATOR

John W. Bules, Marietta, Ohio, assignor to J. & W. Machine & Sheet Metal Co., Marietta, Ohio, a corporation of Ohio

Application July 16, 1941, Serial No. 402,653

6 Claims. (Cl. 98—110)

This invention relates to ventilators for doors, transoms, windows, ceilings, floors, walls or other openings.

An object of this invention is to provide a ventilator structure which will eliminate drafts and substantially all light.

Another object of this invention is to provide in a ventilator an improved louver construction in the form of substantially V-shaped louvers and rockable shutters or closures extending from the inside of the angle of one louver in the direction of an adjacent louver for regulating the passage of air therebetween.

A further object of this invention is to provide in a ventilator of this type an improved means for operating the regulating members as a unit.

A further object of this invention is to provide in a ventilator an improved frame structure of channel construction and an improved means for securing the louvers to the frame structure so as to provide a rigid frame and louver structure.

A further object of this invention is to provide in a ventilator an improved louver which is so constructed as to protect the shutter in any position of the latter so that the shutter cannot be readily bent or damaged.

To the foregoing objects and to others which may hereinafter appear, the invention consists of the novel construction, combination and arrangement of parts as will be more specifically referred to and illustrated in the accompanying drawings wherein is shown an embodiment of the invention, but it is to be understood that changes, variations and modifications may be resorted to which fall within the scope of the invention as claimed.

In the drawings:

Figure 1 is a detail front elevation of a ventilator constructed according to an embodiment of this invention.

Figure 2 is a sectional view taken on the line 2—2 of Figure 1.

Figure 3 is a sectional view taken on the line 3—3 of Figure 1.

Figure 4 is a sectional view taken on the line 4—4 of Figure 3.

Figure 5 is a sectional view taken on the line 5—5 of Figure 3, and

Figure 6 is a fragmentary perspective view of an end portion of one of the louvers.

Referring to the drawings, the numeral 10 designates generally an inverted U-shaped frame structure which is formed of vertically disposed side frame members 11 and 12 of channel shape and an upper channelled-shaped frame member

13. The channel members 11 and 12 are disposed in opposed relation with the channels thereof opening outwardly as shown in Figure 4. The upper channel member 13 is disposed in an inverted position and is provided at the opposite ends thereof with extensions 14 which are formed as continuations of the opposite sides thereof and which extend through slots or openings 15 formed in the webs or bights 16 and 17 of the channel members 11 and 12, respectively. The extensions 14 are adapted to be welded or otherwise fixedly secured to the parallel sides 18 and 19 of the channel members 11 and 12, respectively.

15 A plurality of superposed and vertically spaced apart parallel louvers generally designated as 20 are fixedly mounted within the frame structure 10. Each louver 20 is formed in an inverted V-shaped construction as shown in Figure 3 and each louver 20 at the apex thereof is formed with a longitudinal bead or arcuate channel 21. Each louver 20 at its lower edges or the lower edges of the divergent sides 22 thereof is formed with a vertical extension or side 23. The space between the vertical extensions 23 is slightly less than the width of the webs or bights 16 and 17 of the channel members 11 and 12. The extensions 23 at the opposite ends thereof are formed with outwardly extending ears 24 which are adapted to engage through slots 25 and 26 which are formed in the webs 16 and 17, respectively, and these arms or extensions 24 are disposed in face abutting relation to the inner sides of the legs or side members 18 and 19 of the channel members 11 and 12.

30 The ears or extensions 24 are adapted to be spot welded or otherwise fixedly secured to the inner faces of the legs 18 and 19 respectively. The opposite ends 27 of the louvers 20 are adapted to abut against the inner faces of the webs or bights 16 and 17 and if desired may be welded or otherwise fixedly secured thereto.

35 A plurality of shutters or valve members 28 are disposed between adjacent pairs of louvers 20 and each shutter 28 comprises an elongated plate 29 which is formed at its upper edge with a barrel 30 through which a shaft 31 engages. The shaft 31 is adapted to be fixedly secured within the barrel 30 so that rocking of the shaft 31 will effect 40 rocking of the shutters 28. The opposite ends of the shafts 31 are adapted to be journalled in the central portions of the webs 16 and 17. The shutter 28 also includes a right angularly disposed extension 32 and an offset extension 33 which is disposed in parallel relation with the

body 29 of the shutter 28. The offset extension 33 is adapted to contact with a succeeding or adjacent bead 21 as shown in Figure 3 when the shutter 28 is in a closed position. When the shutter 28 is in a fully open position, the extension 33 will assume the position shown in dotted lines in Figure 3 and will contact with an adjacent vertical side member 23.

In order to provide a means whereby the shutters 28 may be operated as a single unit, I have provided a link 34 which is fixedly secured to an end of the shaft 31, there being as many links 34 as there are shafts 31 and shutters 28. When the shutters 28 are in a closed or vertical position the links 34 will be disposed in the positions shown in Figure 2. The links 34 are connected together at one end thereof by a vertically disposed connecting bar 35 which is pivotally secured to the adjacent ends of the links 34 by pivot members 36. The opposite ends of the links 34 are connected together by a second connecting bar 37 which is connected to the opposite ends of the links 34 by pivot members 38. The bars or connecting members 35 and 37 are disposed in a parallel relation and will be so disposed in any position of the shutters 28.

At a point intermediate the length of the bars 35 and 37, I have provided a shutter operator generally designated as 39. The operator 39 includes a plate 40 which is pivotally connected as at 41 and 42 to the connecting bars 35 and 37 and is also fixedly secured as at 43 to an end of one of the shafts 31. The plate 40 has formed integral therewith a stem 44 which extends loosely through an elongated slot or opening 45 formed in an adjacent side member or leg 19 of the channel member 12. A handle or knob 46 may be fixedly mounted on the stem 44 so that rocking of the operator 39 will effect rocking of the shutters 28 as a unit to either open or closed position.

In the use and operation of this ventilator structure the frame structure 10 is adapted to be fixedly mounted in a desired opening and the operator 39 is positioned in a convenient location for operation of the several shutters 28. The frame structure 10 is disposed with the louvers 20 in the position shown in Figure 3 so that any water or moisture striking the louvers will readily flow downwardly therefrom on the outer sides thereof. Any air passing between adjacent pairs of louvers 20 will initially move upwardly between the confronting or adjacent sides of adjacent pairs of louvers and will then be turned downwardly on the opposite side of the ventilator structure so that this ventilator will prevent drafts of air passing directly therethrough. The formation of the louvers 20 in substantially V-shape also provides a protective structure for the shutters so that these shutters will be substantially entirely enclosed within each louver and will not be subject to damage.

While I have shown the operator 39 mounted at the right end of the ventilator structure shown in Figure 1, it will be apparent that this operator may be shifted to the opposite end of the ventilator structure, where desired.

What I claim is:

1. A ventilator comprising a U-shaped frame disposed in inverted position, a plurality of parallel spaced apart inverted V-shaped louvers fixed in said frame, a shutter swingably supported from the apex of each louver having a width to extend down from the inside of the apex of one louver to engage the top or outside

of the apex of an adjacent lower louver, and a common operator for said shutters.

2. A ventilator comprising a frame member, a plurality of parallel spaced apart inverted V-shaped louvers fixed in said frame, a shutter disposed between each pair of louvers having a width to extend down from the inside of the apex of one louver to engage the top or outside of the apex of an adjacent lower louver, means dependably and swingably supporting said shutter from the apex of a louver, and a common operating means for said shutters.

3. A ventilator comprising a frame structure formed of outwardly facing channel members having pairs of vertically spaced slots through the webs thereof, a plurality of parallel spaced apart inverted V-shaped louvers within said frame, a pair of arms at each end of each louver extending through said slots and fixed to the opposed sides of said channel members, a shutter between each pair of louvers having a width to extend down from the inside of the apex of one louver to engage the top or outside of the apex of an adjacent lower louver, means swingably mounting said shutters from the apex of said louvers, and a common operator for said shutters.

4. A ventilator comprising a frame structure formed of outwardly facing channel members having pairs of vertically spaced slots through the webs thereof, a plurality of parallel spaced apart inverted V-shaped louvers within said frame, a pair of arms at each end of each louver extending through said slots and fixed to the opposed sides of said channel members, a shutter between each pair of louvers having a width to extend down from the inside of the apex of one louver to engage the top or outside of the apex of an adjacent lower louver, a longitudinal bead carried by each louver at the apex thereof, means engageable in said bead swingably supporting said shutters between adjacent pairs of said louvers, and a common operating means for said shutters.

5. A ventilator comprising a frame structure formed of outwardly facing channel members having pairs of vertically spaced slots through the webs thereof, a plurality of parallel spaced apart inverted V-shaped louvers within said frame, a pair of arms at each end of each louver extending through said slots and fixed to the opposed sides of said channel members, a shutter between each pair of louvers having a width to extend down from the inside of the apex of one louver to engage the top or outside of the apex of an adjacent lower louver, a longitudinal bead carried by each louver at the apex thereof, means engageable in said bead swingably supporting said shutters between adjacent pairs of said louvers, each shutter having a laterally offset free edge portion engageable with the bead of an adjacent lower louver when said shutter is in closed position, and a common operating means for said shutters.

6. A ventilator comprising a frame structure formed of outwardly facing channel members having pairs of vertically spaced slots through the webs thereof, a plurality of parallel spaced apart inverted V-shaped louvers within said frame, a pair of arms at each end of each louver extending through said slots and fixed to the opposed sides of said channel members, a shutter between each pair of louvers having a width to extend down from the inside of the apex of one louver to engage the top or outside of the

apex of an adjacent lower louver, a longitudinal bead carried by each louver at the apex thereof, a barrel carried by a longitudinal edge of each shutter, a shaft fixedly mounted in said barrel and having the opposite ends thereof projecting from said barrel and journalled in the webs of said pair of channel members, a link fixed to an end of each shaft and disposed in the chan-

nel of one of said pair of channel members, a pair of parallel connecting bars, means pivotally securing said bars to the opposite ends of links, and an operator pivotally connected with said bars and extending laterally of said frame for operating all of said shutters in unison.

JOHN W. BULES.
